UNITED STATES PATENT OFFICE.

THOMAS H. PATENALL, OF WILKINSBURG, PENNSYLVANIA, ASSIGNOR TO THE UNION SWITCH AND SIGNAL COMPANY, OF SWISSVALE, PENNSYLVANIA, A CORPORATION OF PENNSYLVANIA.

STAFF-LOCK FOR SWITCH-LEVERS.

SPECIFICATION forming part of Letters Patent No. 720,961, dated February 17, 1903.

Application filed October 28, 1902. Serial No. 129,137. (No model.)

To all whom it may concern:

Be it known that I, THOMAS H. PATENALL, a citizen of the United States, residing at Wilkinsburg, in the county of Allegheny and State 5 of Pennsylvania, have invented certain new and useful Improvements in Staff-Locks for Switch - Levers, of which the following is a specification.

My invention relates to a staff - lock for 10 switch-levers.

I will describe a staff-lock for a switch-lever embodying my invention and then point out the novel features thereof in claims.

In the accompanying drawings, Figure 1 is 15 a front elevation of a switch-lever and staff-lock embodying my invention. Fig. 2 is a side elevation, partly broken away to show a middle part. Fig. 3 is a view, partly broken away and partly in section, of a staff-lock embodying my invention, the section being taken 20 on the line 3 3 of Fig. 4. Fig. 4 is a view, partly in elevation and partly in transverse section, of the parts shown in Fig. 3, the section being taken on the line 4 4 of Fig. 3. Fig. 5 is a view, partly in elevation and partly 25 in vertical section, of the staff-lock shown in Fig. 3 with the parts in a different position, the section being taken on the line 5 5 of Fig. 6. Fig. 6 is a view, partly in elevation and 30 partly in transverse section, of the parts shown in Fig. 5, the section being taken on the line 6 6 of Fig. 5. Figs. 3, 4, 5, and 6 are drawn to a larger scale than Figs. 1 and 2.

Similar letters of reference designate corresponding parts in all of the figures.

I will premise that wherever I herein use the term "staff-lock" I mean a lock which is adapted to be operated by a specially-formed key, which is called a "staff." In some uses 40 of this invention in connection with railways the staff is given certain exclusive rights, so that the possessor of the staff may act freely under instructions.

A particular use of this invention may be 45 mentioned in connection with what is known as the "staff" system of signaling used advantageously on signal-track roads having turnouts or branch connections between staff-stations. A train moving in one direction

from one staff-station is given a staff, and it 50 will therefore have the right of way over the section of track between the staff-station from which it started to the next staff-station, at which station it delivers the staff. Obviously, then, the locking of switch-points included 55 in a railway controlled by a staff adds to the safety of such a system. In locking switches the lever is locked only in its normal position—that is, when the switch-points are set for the main track—and the staff can only be 60 withdrawn from the lock after the switch-lever is in its normal position and the locking means set. This insures the proper setting of the switch-points and acts as a check upon 65 carelessness of railroad employees.

Referring now to the drawings, A designates a switch-stand, which may be secured to a suitable support by means of lugs *a*, and B a switch - lever suitably mounted in the switch-stand so as to be rocked on a pivot. 70 One end of the lever B is suitably connected by any desired means to the switch-points, and the lever is provided with the usual latch *b*, which is operated from a latch-handle *b'* through a rod *b*². *b*³ designates a quadrant, with which the latch *b* coacts. In one position of the lever the latch is behind one end *b*⁴ of the quadrant, and in the other position of the lever the latch is behind the end *b*⁵ of the quadrant. It is contemplated by my 75 invention to lock the lever B in only one of its two positions, and this I accomplish by a locking means about to be described.

The locking means are inclosed in a suitable casing C, which is connected with the 85 lever B and moves with it. One wall of the casing—as, for example, *c*—is preferably detachable from the remaining wall of the casing, and it is provided with an opening through which the staff D is inserted. The 90 plate is also provided with a projection *c'*, (here shown as being a part of the plate,) the function of which will be hereinafter explained. The plate *c* may conveniently be termed an "escutcheon-plate." A hinged 95 cover *c*² is provided for closing the opening in the escutcheon-plate, and a lock *c*³ is provided for retaining the cover over the escutche-

eon-plate. The casing is also preferably arranged to include the usual latch-spring, which surrounds the latch-rod. The locking means are here shown as comprising a socket 5 or sleeve d , which is rotated by the staff, a cam d' , rotatable with the socket or sleeve, and a lever d^2 for engaging the latch b . One end of the socket or sleeve is journaled in the escutcheon-plate c , and the other end of 10 which is provided with a plate d^3 , which acts as a plug. The plate d^3 is removably attached to the socket d , and one face of the plate is provided with a projection, rib, or lug d^4 , which is engaged by the staff D , and 15 the opposite face of the plate is provided with a trunnion d^5 , which rotates in a suitable bearing provided for it in the casing C . d^6 designates ribs provided on the socket d' , with which springs d^7 coact. The function of 20 these springs is to prevent a too free movement of the sleeve and of the parts connected therewith. The cam d' is here shown as being integral with the socket d , though it may be a separate piece and connected to the 25 socket in any desired manner. The lever d^2 is pivoted at one of its ends to the casing C , and when the latch is in position behind the quadrant the lever engages over the latch and cam d' engages over the lever. The position of the parts in the position just described is illustrated in Figs. 3 and 4.

The staff D (see Fig. 6) is here shown as having a longitudinal groove d^9 and a transverse groove d^{10} , which leads from the longitudinal groove. These grooves are adapted 35 to coact with the projection c' of the escutcheon-plate. It will be seen, therefore, that when the staff is inserted in the socket and turned the projection c' will project into the 40 transverse groove and prevent the staff from being withdrawn until it is turned again to bring the longitudinal groove into alignment with the projection c' . When the socket is turned, and this is accomplished through the 45 projection d^4 , fitting in a recess or groove in the end of the staff, the cam d' is moved to the position shown in Fig. 5. The latch b can then be lifted, the lever thrown, and the latch b dropped behind the other end of the 50 quadrant. With the latch b behind the end b^5 of the quadrant the lever d^2 rests on the quadrant and a portion of it is in the path of movement of the cam d' , thus preventing its being turned to such position that the staff 55 can be withdrawn. It will therefore be seen that the staff can only be removed from the lock when the lever B is in the normal position, which is the position shown in Fig. 2. The term "normal" is herein used in apposition to the term "reverse," which latter is 60 the position of the lever when the switch-points are set to open the main line or track.

The advantages of the invention herein de-

scribed will be apparent to those skilled in the art.

What I claim as my invention is—

1. The combination with a switch-lever, of a latch for said lever, means for locking the latch to hold the lever in one position and a staff for operating the locking means.
  2. The combination with a switch-lever, of a latch for said lever, a quadrant with which the lever coacts, and means operated by a staff for holding the latch locked with the quadrant in one position of the switch-lever.
  3. The combination with a switch-lever, of a latch for said lever coacting with a quadrant, and a locking means carried by the lever and adapted to lock the latch in engagement with the quadrant in one position of the switch-lever.
  4. The combination with a switch-lever, of a latch for said lever, and a locking means for said latch comprising a pivoted lever for engaging the latch, a movable cam for holding said lever from movement when in one position, and means for rotating the cam.
  5. The combination with a switch-lever, of a latch for said lever and a locking means for said latch comprising a pivoted lever for engaging the latch, a rotatable cam for coaction with the lever and a staff for rotating the cam.
  6. The combination with a switch-lever having a movement from normal to reverse, of means for locking the lever in normal position, and a staff for operating said locking means to release the switch-lever, said staff being prevented by the locking means from being removed when the switch-lever is out of normal position.
  7. The combination with a switch-lever having a latch, of a quadrant with which the latch coacts, and a locking means for the latch comprising a socket adapted for rotation by a staff, a cam carried by said socket, and a lever.
  8. The combination with a switch-lever having a latch, of a casing carried by said lever, one wall of which is provided with an opening for a staff, a locking means within said casing for the latch and a pivoted cover for closing the opening in said casing.
  9. The combination with a switch-lever having a latch, of a spring therefor, a casing carried by said lever for inclosing said spring and a locking means for the latch also carried by said casing and operated by a staff.
- In testimony whereof I have signed my name to this specification in the presence of two subscribing witnesses.
